FLEXIBLE METAL FREEZING TRAY

Harvey D. Geyer, Dayton, Ohio, assignor, by
mesne assignments, to General Motors Corpora-
tion, Detroit, Mich., a corporation of Delaware

Application February 16, 1933, Serial No. 656,990

8 Claims. (Cl. 62—108.5)

This invention relates to freezing containers, especially such as are adapted for home use in the freezing compartments of electric refrigerators.

5 The general object of the invention is to provide a flexible metallic freezing tray of simple and efficient construction having a series of individual ice pockets, and which may be easily flexed by hand to remove the frozen ice blocks 10 without first melting the frozen bond between the ice blocks and the tray.

Other features of the invention comprise the various details of structure and the method of making such a flexible metallic tray as will provide economy in the manufacture thereof and 15 efficiency and long life in use.

Further objects and advantages of the present invention will be apparent from the following description, reference being had to the accompanying drawing, wherein a preferred embodiment of one form of the present invention is clearly shown.

In the drawing:

Fig. 1 is a plan view of a two-row ten-block 25 freezing tray made according to this invention.

Fig. 2 is a vertical section taken on line 2—2 of Fig. 1.

Fig. 3 is an end elevation of the tray of Fig. 1.

Similar reference characters refer to similar 30 parts throughout the several views.

The tray shown in the drawing for the purpose of illustrating the invention is pressed and drawn from a single piece of sheet metal, preferably copper, and has two rows of ice pockets 35 10 formed therein. The two rows of pockets have an intervening air space 11 therebetween (see Fig. 3) and the two rows are joined together by the fold 12 in the sheet metal. Likewise the individual pockets 10 in each row have 40 an intervening air space 13 therebetween (see Fig. 2) and the pockets are joined together by the folds 14 at the upper edges of the pockets 10. All of these pockets 10 are shown as having 45 an elongated shape and both the side and end walls thereof are inclined so that the cross section at the top of each pocket is considerably larger than that at the bottom. The structure so far described provides something very similar 50 to an ordinary sheet metal cookie pan for baking cookies.

Now the fundamental idea of this invention is to add to the above-described structure ridges or folds in the metal walls of each pocket 10, whereby each individual pocket 10 may be expanded in size by flexure of the metal at such

ridges or folds in order to facilitate the removal of the frozen ice blocks from the pockets. For this purpose each pocket 10 is provided with a continuous ridge or corrugation 15 extending entirely across the bottom and the two opposed end walls thereof so that each pocket may be expanded in size by the flexure of the metal at the continuous ridge 15 thereacross, that is, the pockets may be stretched to a slightly increased size by any force which tends 10 to flatten out the ridges 15 therein. Such a force may be applied to the tray by flexing the tray as a unit upward at its center and downward at its two ends, which flexing may be easily done with the hands. Obviously such a 15 bending of the tray as a unit will tend to pull the long sides 16 of each pocket further apart, and the ridge 15 in each pocket will yield under this tendency to permit the side walls 16 of each pocket to separate a small distance. Ob- 20viously such a separation will free the side walls 16 from their frozen bond to the ice block. Simultaneously the slight flattening of the ridges 15 will so change the shape of the bottom wall and two end walls of each pocket 10 that 25 the ice block will be freed from these walls also. The ice blocks may then be dumped out by inverting the tray or they may be picked out individually from the pockets 10.

In order that the two-row tray shown in the 30 drawing may be easily flexed as a unit as described in the preceding paragraph, the separate ridges 15 in the one row are aligned with the separate ridges 15 in the other row. A hole 20 is provided in the metal fold 12 between 35 each pair of aligned ridges 15 to avoid the stiffening effect of the fold 12 against the longitudinal bending of the tray as a unit. This will be clear from viewing Fig. 1. Obviously if the holes 20 were omitted and the metal fold 12 thereby made continuous the full length of the tray, this fold 12 would greatly stiffen the tray against the above described longitudinal bending. However, with the fold 12 cut away at the holes 20, as shown in Fig. 1, it can have no 40 stiffening effect against the expansion in size of the pockets 10 by the longitudinal bending of the tray as a unit as described above.

Obviously, if desired, only a single-row tray 45 may be made according to this invention and operation to remove the frozen ice blocks therefrom would be substantially the same as above described.

While the form of embodiment of the present 50 invention as herein disclosed, constitutes a pre-

ferred form, it is to be understood that other forms might be adopted, all coming within the scope of the claims which follow.

What is claimed is as follows:

- 5 1. A freezing tray comprising a sheet metal container having a row of individual ice pockets formed by folds in the sheet metal, said pockets each having a continuous ridge formed in the walls thereof and extending in a plane transverse to the length of said row of pockets whereby each pocket may be expanded in size by flexure of its walls along said continuous ridge to facilitate removal of the frozen contents.
- 10 2. A flexible freezing tray integrally formed from flat sheet metal and having a row of ice pockets therein, said ice pockets being defined by inwardly projecting transverse folds in the sheet metal, said transverse folds being continuous through the upper edges of the side walls 20 of the tray so as to materially facilitate the bending of said tray about an axis parallel to said folds when filled with ice, whereby to permit the loosening of the frozen bond between the tray and its ice contents.
- 25 3. A flexible freezing tray integrally formed from flat sheet metal and having a row of ice pockets therein, said ice pockets being defined by inwardly projecting transverse folds in the sheet metal, said transverse folds extending through the upper edge of the outer side walls 30 of the tray in such manner as to render said outer side walls extensible and to facilitate the bending of said tray transverse the length of said row of ice pockets.
- 35 4. A flexible freezing tray comprising a sheet metal container having a row of ice pockets, said tray having a series of inwardly extending open folds formed in the walls thereof and extending in a plane substantially transverse the length of

said row of pockets, said open folds extending entirely through the upper edges of the tray walls and thereby providing a series of continuous lines of relatively easy flexure transversely of the tray.

5. A flexible metal freezing container integrally formed from flat sheet metal and adapted to be filled with water to be frozen, said container having a series of inwardly extending open folds spaced apart and each lying in substantially a single plane transverse the bottom and side walls of said container, said open folds extending entirely through the upper edges of said side walls and providing a series of lines of relatively easy flexure extending transversely 15 across the container.

6. A flexible sheet metal open-top freezing container adapted to be filled with water to be frozen, said container having an inwardly extending open fold lying in substantially a single 20 plane transverse the bottom and side walls of the container, said open fold extending entirely through the upper edges of said side walls and providing a line of relatively easy flexure.

7. A flexible sheet metal freezing tray having 25 a water-retaining pocket, said pocket having a continuous open ridge lying in substantially a single plane across the bottom and side walls of said pocket, said open ridge extending entirely through the upper edges of the side walls of said 30 pocket and providing a line of relatively easy flexure.

8. A flexible metal open-top freezing tray having two opposed longitudinally stretchable outer side walls and a stretchable corrugated metal 35 plan area interconnecting said stretchable side walls and defining a series of ice block compartments.

HARVEY D. GEYER.
